UNITED STATES PATENT OFFICE.

SIDNEY AUGUSTIN ROUSSEAU, OF DE WITT, ARKANSAS.

FLUID-PRESSURE COUPLING.

1,343,852.

Specification of Letters Patent. Patented June 15, 1920.

Application filed November 21, 1919. Serial No. 339,644.

To all whom it may concern:

Be it known that I, SIDNEY A. ROUSSEAU, a citizen of the United States, residing at De Witt, in the county of Arkansas and 5 State of Arkansas, have invented certain new and useful Improvements in Fluid-Pres-
sure Couplings; and I do hereby declare the following to be a full, clear, and exact de-
scription of the invention, such as will en-
able others skilled in the art to which it
appertains to make and use the same, refer-
ence being had to the accompanying draw-
ings, and to the letters and figures of refer-
ence marked thereon, which form a part of
15 this specification.

This invention relates to new and useful improvements in automatic couplers for train pipes, and comprises a simple and ef-
ficient apparatus of this nature, and in the
20 provision of means whereby, as two simi-
larly equipped trains come together, the
fluid pressure pipes may automatically be
coupled and the valves automatically opened
and closed when cars containing the ap-
paratus are uncoupled.

The invention comprises various other de-
tails of construction, combination and ar-
rangement of parts which will be herein-
after fully described, shown in the accom-
30 panying drawings and then specifically de-
fined in the appended claims.

My invention is illustrated in the accom-
panying drawings which, with the numerals
of reference marked thereon, form a part
35 of this application, and in which:

Figure 1 is a side elevation of one of the
couplers.

Fig. 2 is a sectional view on line 2—2 of
Fig. 1.

40 Fig. 3 is an end view partially in cross sec-
tion and illustrating the support for holding
the coupler.

Fig. 4 is a sectional view on line 4—4 of
Fig. 2.

45 Fig. 5 is an enlarged central sectional
view through two heads coupled together.

Fig. 6 is a side elevation showing the de-
vice attached to the truck of a car.

50 Fig. 7 is a front elevation of the form
shown in Fig. 6.

Fig. 8 is a plan view of the device mount-
ed on attaching bars.

Fig. 9 is a sectional view through a
slightly modified form of the invention.

Fig. 10 is a detail sectional view, showing 55
the heads arranged for one pipe only, and

Fig. 11 is an end view of a coupler head.

Reference now being had to the details of
the drawings by numerals:

1 designates a cylinder having a circular 60
outlined head 2, shown in elevation in Fig.
3 of the drawings, and provided with aper-
tures 3, 4, 5 and 6, apertures 3 and 4 having
gaskets 7 mounted therein.

A fluid pressure pipe 8 has its forward 65
open end engaging a recess in said cylinder
head 2 and communicates with the opening 3,
and has a valve 9 mounted in a suitable cas-
ing 10, and 11 is a stem secured to said valve
and extending through an opening 8' in the 70
cylinder 1, and also in a hole 12 in the sta-
tionary cylindrical casing 13, the cylinder
1 having a telescoping movement therein
for a purpose which will be presently de-
scribed. Said valve casing 10 is connected 75
to a pipe section 14 passing through the rear
end of the cylinder 1 and held securely
therein by means of jam nuts 15. The pipe
14 is connected by an elbow 16 of the pipe
17 through which fluid from any suitable 80
source is to be conveyed. Mounted within
the opening 5 in the cylinder head is a
tapering nipple 18, which communicates
through a duct 21 with the recess 4 formed
in the cylinder head. 85

A fluid pressure tube 18 communicates
with said nipple at one end, and its other
end is connected to a casing having a valve
23 with a stem 24 which passes through an
elongated slot 25 formed in the wall of the 90
cylinder 1, and also through an opening 26
formed in the wall of the cylinder 13. A
pipe 27 is connected to the casing of valve
23 and passes through the rear end of the
cylinder 1 and is adapted to be connected by 95
an elbow 28 with a train pipe. A fluid pres-
sure cylinder 29 has its forward end seated
in a recess in the cylinder head and closed,
and telescoping within said fluid pressure
cylinder is a solid cylindrical piston rod 30 100
movable through a suitably packed gland 31,
and its opposite end passes through the rear
end of the cylinder 13 and is held securely
thereto by means of the jam nuts 32.

A short pipe connection 33 is formed be- 105
tween the fluid pressure cylinder 29 and
the tubular member 18, permitting the fluid
pressure to pass from the member 18 to the

cylinder 29 for the purpose of imparting a pressure intermediate the cylinder head and the end of the piston rod to hold said nipples coupled together when the two couplers 5 come together.

A nipple 35' is mounted in an opening in the outer end of the spring pressed cylinder 1 and communicates with a fluid pressure member 34, which in turn is connected to a valve casing 36 having a valve 37. A stem 38 passes through a slot 39 in the cylinder 1 and a slot 40 in the cylinder 13.

A pipe 41 is connected to the casing 36 and passes through the rear wall of the cylinder 1, and is connected through the medium of the elbow 42 with a pipe 43, which latter passes through a slot 44 in the cylinder 13. Said cylinder 13 has projecting trunnions 52, supported by the members 46, on which are forked arms 47, the inner edges of which are tapering, as shown clearly in Figs. 1 and 4 of the drawings. The cylinder 1 is provided with oppositely projecting lugs 48, which have opposite edges 49 inclined and tending to properly align the two cylinders, when thrown to the position shown in Fig. 2 of the drawings, through the medium of the coiled spring 50, which bears between the cylinder head and a peripheral flange 18' formed in the adjacent end of the cylinder 13.

Upon reference to Figs. 3 and 4 of the drawings, it will be noted that the cylinder 13 is mounted upon trunnions 52 supported from the swiveled frame 46, said frame 46 being mounted on trunnions 51, supported by frame 46', giving the cylinder a universal movement when the arms 48 are out of engagement with the inclined edges of the forked arms 47.

In Figs. 6 and 7 of the drawings, I have shown mountings for the couplers, consisting of the truss bars 54 to which are bolted the parallel bars 55, which support at their outer ends the coupling head, the end view of Fig. 7 showing the brace bars 56 to further reinforce and hold the parallel bars 55 rigid.

50 In Fig. 9 of the drawings I have shown a slight modification of the invention, in which the cylinder 58 is provided with a cylinder head 59, and 60 is a cylinder within which the cylinder 58 telescopes, the latter 55 having laterally projecting lugs 61 movable through the slot 62 in the cylinder 60. In this modified form a single tubular pipe 63 is provided which communicates at its forward end with an opening 63' in the end wall 60 of the cylinder 58 and 64 is a tapering nipple, also seated in the opening 63'. Said opening 63' communicates through the medium of a duct 66 with a recess 67 in the cylinder head, and in which the nipple 64 is adapted

to be inserted when two coupler heads of 65 similar construction come together.

Mounted in a groove in the recess is a suitable gasket 68 in order to insure a tight fit. A pipe 69 has its forward end seated in a recess in the cylinder head 66 closing 70 said pipe, and has its other end connected to a flexible pipe 70. The two pipes 63 and 69 have a communicating pipe section 71 through which fluid pressure may pass into the pipe 69 for the purpose of assisting in 75 holding the connected ends of the tubular members securely together. The rear end of the pipe 63 is closed and works through a suitable gland 72, and has an aperture 73 in the wall thereof which, when the coupler 80 heads are connected, registers with a port 74 with which the pipe 75 communicates. A spring 76 bears between the cylinder head 59 and the flange 63' upon the cylinder 60 and tends to normally hold the cylinder 58 85 to its outer limit.

In Fig. 10 is illustrated a modified form of the coupler heads connected together. Leading through the bottom of the recess in the cylinder head is an exhaust vent 77 90 through which any leakage of gas, which may be pocketed in the recess, may escape.

In operation, when two coupler heads, similarly constructed, come together, the tapering nipples 35' and 18', upon one 95 coupler head, will engage respectively the aperture 3 and the recess 4 formed in the cylinder head of an opposing coupler; and similar nipples in the opposing member will engage an aperture and recess upon the other 100 cylinder head, in the manner shown in Fig. 5 of the drawings. As said nipples approach each other, they will be held in alignment by means of the forked members 47 on 26 and 26' and the wedge-shaped members 48 projecting from the circumference of the cylinder 1, and when the nipples are connected as described, the cylinders 1 will be moved back, bringing the springs 50 into compression, and as the cylinders 1 move 110 within the cylinders 13, the valve stems will be turned, causing the valves to open and permit the fluid pressure to pass through the tubular members and nipples from one coupler head to the other.

115 A full pressure in the tubular member 18 will enter the fluid pressure cylinder 29 and act upon the inner surface of the cylinder head 2 and upon the piston 30, causing said tapering nipples to engage their respective apertures and recesses, and be held securely against the gaskets therein and thus form a tight joint.

120 As the cylinders 1 telescope within the cylinders 13, the lugs 48 will draw away from the inclined edges of the arms of the forked members 47, which will permit the cylinders 125 to have free swinging movements vertically

and horizontally, at the same time holding the nipples securely connected, so that the fluid pressure may pass freely without interruption incident to vibration and angularity.

When it is desired to disconnect the fluid pressure coupler heads, it may be done by the disconnecting of the usual couplers upon the cars, and as the nipples withdraw from their respective apertures and recesses, the springs 50 will return the cylinders 1 to their normal outer limits, and in such movement the stems of the valves will shut off the supply and the fluid pressure within the tubular members 29 will exhaust to the atmosphere and relieve the inner faces of the cylinder heads from pressure from that source.

By the provision of a fluid pressure coupler made in accordance with my invention, it will be noted that a simple and efficient apparatus is provided which may be easily and quickly applied to all cars, and connected to the train pipes, and which is thoroughly automatic in its action, the valves being turned on as set forth when the heads are coupled and automatically closed when disconnected.

What I claim to be new is:

1. An automatic fluid pressure coupler for train pipes, comprising two telescoping cylinders, one stationary and the other movable and provided with apertures in its outer end wall, nipples projecting from said apertures, fluid pressure pipes communicating with said nipples, valves in said pipes automatically opening and closing as the movable cylinder moves in opposite directions, the outer end of said movable cylinder having a recess and an aperture and also a duct leading from said recess to one of said nipples, and a valve regulated fluid pressure member communicating with said last mentioned aperture and adapted for connection to a train pipe.

2. An automatic fluid pressure coupler for train pipes, comprising two telescoping cylinders, one stationary and the other movable and provided with apertures in its outer end wall, nipples projecting from said apertures, fluid pressure pipes communicating with said nipples, valves in said pipes automatically opening and closing as the movable cylinder moves in opposite directions, the outer end of said movable cylinder having a recess and an aperture and also a duct leading from said recess to one of said nipples, a valve regulated fluid pressure member communicating with said last mentioned aperture and adapted for connection to a train pipe, and means for holding the nipples upon one coupler head in alinement with a recess and aperture upon an opposing head, as the heads come together.

3. An automatic fluid pressure coupler for

train pipes, comprising two telescoping cylinders, one stationary and the other movable and provided with apertures in its outer end wall, nipples projecting from said apertures, fluid pressure pipes communicating with said nipples, valves in said pipes automatically opening and closing as the movable cylinder moves in opposite directions, the outer end of said movable cylinder having a recess and an aperture and also a duct leading from said recess to one of said nipples, a valve regulated fluid pressure member communicating with said last mentioned aperture and adapted for connection to a train pipe, means for holding the nipples upon one coupler head in alinement with a recess and aperture upon an opposing head, as the heads come together, and means for applying fluid pressure to the inner face of the head of each movable cylinder as said heads are coupled together.

4. An automatic fluid pressure coupler for train pipes, comprising two telescoping cylinders, one stationary and the other movable and provided with apertures in its outer end wall, nipples projecting from said apertures, fluid pressure pipes communicating with said nipples, valves in said pipes automatically opening and closing as the movable cylinder moves in opposite directions, the outer end of said movable cylinder having a recess and an aperture and also a duct leading from said recess to one of said nipples, a valve regulating fluid pressure member communicating with said last mentioned aperture and adapted for connection to a train pipe, means for holding the nipples upon one coupler head in alinement with a recess and aperture upon an opposing head, as the heads come together, and means for applying fluid pressure to the inner face of the head of each movable cylinder as said heads are coupled together, comprising a fluid pressure cylinder connected at its outer end to the head of the movable cylinder and communicating with one of said fluid pressure pipes, and a piston telescoping into said fluid pressure cylinder.

5. An automatic fluid pressure coupler for train pipes, comprising two telescoping cylinders, one stationary and the other movable and provided with apertures in its outer end wall, nipples projecting from said apertures, fluid pressure pipes communicating with said nipples, valves in said pipes automatically opening and closing as the movable cylinder moves in opposite directions, the outer end of said movable cylinder having a recess and an aperture and also a duct leading from said recess to one of said nipples, a valve regulated fluid pressure member communicating with said last mentioned aperture and adapted for connection to a train pipe, means for holding the nipples upon one coupler head in alinement with a recess and aperture upon an opposing head, as the heads come together.

with a recess and aperture upon an opposing head, as the heads come together, and means for applying fluid pressure to the inner face of the head of each movable cylinder as said heads are coupled together, comprising a fluid pressure cylinder connected at its outer end to the head of the movable cylinder and communicating with one of said fluid pressure pipes, and a piston secured at its inner end to the stationary cylinder and projecting into said fluid pressure cylinder.

6. An automatic fluid pressure coupler for train pipes, comprising two telescoping cylinders, one stationary and the other movable, said cylinders having registering slots and said movable cylinder being provided with apertures in its outer end wall, nipples mounted in said apertures, fluid pressure pipes communicating with said nipples, valves in said pipes and having stems projecting through said registering slots, a central fluid pressure cylinder connected at its outer end to said end wall of the movable cylinder, and communicating with one of said fluid pressure pipes, a stationary piston projecting into said central fluid pressure cylinder, said outer end wall of the movable cylinder having an aperture and recess and also a duct communicating with said recess and with one of said fluid pressure pipes, a valved pressure pipe communicating with said last mentioned aperture, and means for holding the nipples upon the coupler in alignment with the recess and aperture in an opposing coupler head, as said heads come together.

7. An automatic fluid pressure coupler for train pipes, comprising two telescoping cylinders, one stationary and the other movable, said cylinders having registering slots and said movable cylinder being provided with apertures in its outer end wall, nipples mounted in said apertures, fluid pressure pipes communicating with said nipples, valves in said pipes and having stems projecting through said registering slots, a central fluid pressure cylinder connected at its outer end to said end wall of the movable cylinder, and communicating with one of said fluid pressure pipes, a stationary piston projecting into said central fluid pressure cylinder, said outer end wall of the movable cylinder having an aperture and recess and also a duct communicating with said recess and with one of said fluid pressure pipes, a valved pressure pipe communicating with said last mentioned aperture, said stationary cylinder being provided with trunnions, a support in which said trunnions are journaled, pairs of forked members carried by said support, the adjacent longitudinal edge of each member of a pair being reversely inclined, and wedge-shaped projections upon the movable cylinder adapted to en-

gage the said inclined edges of the forked members to hold the nipples in proper alignment with a recess and aperture in an opposing cylinder head as the couplers come together.

8. An automatic fluid pressure coupler for train pipes, comprising a stationary and a movable cylinder telescoping one within the other, trunnion supporting means for said stationary cylinder, adapted to be attached to the truck of a car, nipples mounted in the outer head of said movable cylinder, fluid pressure pipes communicating with said nipples, automatically actuated valves in said pipes, said outer head of the movable cylinder having a recess and a duct in communication with said recess and one of said nipples, and also an aperture adjacent said recess, a valved pipe communicating with said aperture and adapted to be connected to a train pipe, a fluid pressure cylinder connected at its outer end to the said outer head of the movable cylinder, and communicating with one of said fluid pressure pipes, a stationary piston projecting into said fluid pressure cylinder, and means for alining the nipples of one head with a recess and aperture in an opposed coupler head, as said heads come together.

9. An automatic fluid pressure coupler for trains, comprising a fixed frame for attachment to the truck of a car, a second frame having trunnion connection with the fixed frame, said frames having forked alining members thereon, those upon one frame in planes at right angles to the planes of those on the other frame, two telescoping cylinders, one of which is stationary, pivotal means for supporting said stationary cylinder in said trunnion frame, the other cylinder being movable, and provided with projections co-operating with said forked members to guide the movable cylinder in its longitudinal and axial movements, the outer end wall of said movable cylinder having apertures and a recess, and also a duct communicating with said recess and one of said apertures, nipples in said apertures, fluid pressure pipes communicating with said nipples, valves in said pipes, means for automatically actuating the valves as the movable cylinder telescopes within the stationary cylinder, a fluid pressure cylinder provided with a duct communicating with one of said fluid pressure pipes and a piston fixed to the stationary cylinder and movable within said fluid pressure cylinder.

10. An automatic fluid pressure coupler for trains, comprising a fixed frame for attachment to the truck of a car, a second frame having trunnion connection with the fixed frame, said frames having forked alining members thereon, those upon one frame in planes at right angles to the planes of those on the other frame, two telescoping cylin-

ders, one of which is stationary, pivotal means for supporting said stationary cylinder in said trunnion frame, the other cylinder being movable, and provided with projections coöoperating with said forked members to guide the movable cylinder in its longitudinal and axial movements, said stationary cylinder being provided with longitudinal slots, said projections passing through said slots, the outer end wall of the movable cylinder being provided with apertures and a recess, and also with a duct communicating with said recess and one of said

5 apertures, nipples in said apertures, fluid pressure pipes communicating with said nipples, valves in said pipes, means for automatically actuating the valves as the movable cylinder telescopes within the stationary cylinder, a fluid pressure cylinder provided with a duct communicating with one 15 of said fluid pressure pipes, and a piston carried by the stationary cylinder and movable within said fluid pressure cylinder.

10 In testimony whereof I hereunto affix my signature.

SIDNEY AUGUSTIN ROUSSEAU.
